US00D704133S

(12) **United States Design Patent**
Xu et al.

(10) **Patent No.:** US D704,133 S
(45) **Date of Patent:** ** May 6, 2014

(54) **RECHARGEABLE BATTERY PACK**

(75) Inventors: **Ning Xu**, Nanjing (CN); **Deshun Chen**, Nanjing (CN); **Hua Jiang**, Sharon, MA (US)

(73) Assignee: **Nanjing Optron Scientific, Inc. Ltd.**, Nanjing, Jiangsu (CN)

(**) Term: **14 Years**

(21) Appl. No.: **29/391,311**

(22) Filed: **May 6, 2011**

(51) LOC (10) Cl. **13-02**

(52) U.S. Cl.

USPC **D13/103**

(58) **Field of Classification Search**

USPC D13/102-108, 110, 118-121, 184, 199;
429/96-100, 163, 176

See application file for complete search history.

(57) **CLAIM**

The ornamental design for a rechargeable battery pack, as shown and described.

DESCRIPTION

FIG. 1 is a perspective view of a rechargeable battery pack showing our new design;

FIG. 2 is a top view thereof;

FIG. 3 is a front view thereof;

FIG. 4 is a rear view thereof;

FIG. 5 is a left view thereof;

FIG. 6 is a right view thereof;

FIG. 7 is a bottom view thereof; and,

FIG. 8 is a perspective view of a rechargeable battery pack as a counterweight with a telescope mount thereof. The broken lines showing the telescope mount in the drawings are included for the purpose of illustrating environmental structure and form no part of the claimed design.

1 Claim, 5 Drawing Sheets

FIG. 1 (Amemded)

FIG. 2

FIG. 3

FIG. 4

FIG. 5

FIG. 6

FIG. 7
